UNITED STATES PATENT OFFICE.

EDMUND H. MICKLEWOOD AND HARRY WHIDBOURNE, OF PLYMOUTH,
ENGLAND.

INTERNAL-COMBUSTION ENGINE.

No. 856,790.

Specification of Letters Patent.

Patented June 11, 1907.

Application filed April 8, 1907. Serial No. 367,061.

To all whom it may concern:

Be it known that we, EDMUND HAWTHORNE MICKLEWOOD and HARRY WHIDBOURNE, both subjects of the King of Great Britain, residing respectively at 5 St. Michael's Terrace, Plymouth, in the county of Devon, England, engineer, and 51 Greenbank avenue, Plymouth, in the county of Devon, England, watchmaker, have invented certain new and useful Improvements in Internal-Combustion Engines, of which the following is a specification:

This invention relates to internal combustion engines and to a construction thereof in which an annular extension of the engine piston working in an annular cylinder or chamber formed between an outer wall coaxial with the working cylinder and a fixed sleeve over which the piston trunk slides. According to the present invention this annular chamber is utilized on alternate strokes of the engine for compressing the whole or part of the working charge into the engine cylinder and for compressing a charge for scavenging the engine cylinder, whereby a two stroke cycle engine is obtained, suitable valve controlled passages and ports being provided for this purpose. The opposite ends of the annular chamber or pump cylinder are connected by conduits with the working cylinder so that a compressed charge of air or of combustible gas or vapor or of a mixture of combustible gas or vapor and air is delivered to the working cylinder from one end of the annular chamber during one stroke of the piston, and a scavenging air charge from the other end of the chamber during the return stroke of the piston. The conduits are controlled by valves in such manner that the charge of air or combustible, as the case may be, is first trapped in the annular chamber and then, after compression, allowed to pass into the working cylinder.

In the accompanying drawings, which are more or less diagrammatic, Figure 1 is a central longitudinal section of a vertical type of engine embodying the present invention; Fig. 2 is a central section through an accessory which may be used with the engine; Fig. 3 is a part section of the engine cylinder showing a device for regulating the pressure of the working charge; Fig. 4 is a view similar to Fig. 1, but showing a slightly modified

arrangement of conduits and valves; and Fig. 5 is a section on line 5—5 of Fig. 4.

Referring first to Fig. 1, the piston A operates in the working cylinder B in the usual manner and has a hollow or open ended extension A' which works in an annular chamber B' formed in a pump cylinder co-axial with the working cylinder B. The pump cylinder is formed by the lower portion of the cylinder body or casting, which for this purpose is made of greater internal diameter than the working cylinder, and the chamber B' is formed by said lower portion of the cylinder body or casting and a sleeve B² which is secured within the said lower portion of the cylinder body and fitted to the interior face of the hollow piston trunk. The sleeve is fitted with rings B³ to prevent the escape of any fluid between it and the piston trunk, and the working piston A and pump piston A' are also fitted with rings A², A³ respectively in the usual manner.

A conduit C connects the rear end of the chamber B' with the rear end of the cylinder, but its communication with the cylinder is controlled by a non-return valve C'. At a convenient point of the conduit C is an inlet passage D controlled by a non-return valve D'. The valves C', D' are adapted to admit fluid to the cylinder B and conduit C respectively. The forward end of the chamber B' is connected by a conduit E and port or ports E' with the forward end of the working cylinder in which also are ports B⁴ which communicate with the exhaust conduit, not shown in the drawings, and which are uncovered by the piston A before it reaches the end of the outward stroke. At a convenient point in the conduit E is an outlet passage F controlled by a non-return valve F' adapted to admit fluid to the conduit E.

The operation of this engine is as follows: The piston A is shown in the drawings at the end of the working stroke when exhaust has taken place through the ports B⁴ uncovered by the piston. In this position of the piston the port E' is uncovered and a charge of air or neutral gas, which in the two preceding strokes has first been drawn into the chamber B' in front of the piston A' through the inlet passage F, valve F' and conduit E, and then been compressed in the chamber B' and conduit E, thereby admitted to the working

cylinder. The piston A may be provided with a baffle A⁴ as shown, opposed to the entering fluid so as to deflect the latter and prevent a straight blow through the exhaust ports B⁴, so that a thorough scavenging is effected and the working cylinder is filled with a charge of cool air at atmospheric pressure with only a small admixture of the residual products of combustion. During the working stroke a second charge of air or a combustible charge is drawn into the chamber B' and conduit C in rear of the piston A' through conduit D and valve D', and this charge is compressed in the chamber B' and conduit C on the return or compression stroke of the piston simultaneously with the compression of the charge in the working cylinder. The pressure in the chamber B' and conduit C increases more rapidly however than the pressure in the working cylinder, firstly because compression does not begin in the working cylinder until the exhaust ports B⁴ are covered by the piston A, and secondly because the stroke volume of the piston A' is arranged to be a greater fraction of the total volume of the chamber B' and conduit C than the stroke volume of the working piston A is of the total volume of the cylinder B. Consequently the charge in chamber B' and conduit C will begin to enter the working cylinder practically at the beginning of the compression stroke and will continue to enter until the end of the stroke unless means are provided to relieve the pressure in the chamber B' at any intermediate point of the stroke. During the compression stroke also, the piston A' draws a fresh charge of fluid through conduit F and valve F' into the chamber B' on the front side of the piston A', this charge being trapped by the closing of the valve F' and compressed during the working stroke of the piston until the port E', which remains covered until after the exhaust ports B⁴ are uncovered, is uncovered by the piston A, and the charge compressed in the conduit E and forward end of the chamber B' is then allowed to enter the working cylinder as already described, whereupon the cycle of operations is repeated. If a combustible charge is admitted by the valve D' no other device is required for the admission of fuel to the working cylinder, but when air only is admitted by this valve suitable means must be provided for injecting the fuel. A suitable pump for this purpose is shown in Fig. 2. The pump body G has a screw threaded nipple G' for insertion in the screw threaded hole G² in the cylinder wall which is shown closed by a plug G³ in Fig. 1. A spring controlled plunger G⁴ slides in a longitudinal bore of the casting which communicates on the one hand with a duct G⁵ for admission of fuel to the pump, and on the other hand with a duct G⁶ extending through the nipple G' through which the fuel is injected by the

pump plunger into the working cylinder. The duct G⁶ is controlled by a conical valve G⁷ held on its seat by a spring G⁸, while the duct G⁵ requires no other valve than is provided by the plunger itself which crosses the point at which the duct enters the bore of the pump and as will be seen constitutes a measuring device insuring a constant volume of charge. The plunger G⁴ may be operated by any suitable mechanism and may be arranged to be moved positively in both directions by the actuating mechanism instead of the return stroke being effected by a spring as shown. When it is desired to vary the compression of the working charge there may be provided, in addition to or in lieu of any suitable known means for throttling the charge, a series of ports H formed in a convenient part of the cylinder wall, the inner ends of which ports are uncovered in succession during the latter part of the compression stroke and put into communication with the chamber B' by means of a longitudinal groove A⁵ on the outer face of the piston trunk. The ports H open into a valve chamber H' and are controlled by a slide valve H² by which one or more of the series of ports may be closed. If air only is forced into the working cylinder on the compression stroke the chamber H' is open to the atmosphere, but if a combustible charge is used the chamber H² is connected by a conduit H³ with the conduit D or with the source whence the charge is drawn in through the valve D'. It will be seen that with this arrangement the compression will vary according to the position of the valve H², as if all the ports H are left uncovered by the valve H² the chamber B' will begin to return its charge to the conduit D, or discharge into the atmosphere, as soon as the recess A⁵ in the piston trunk reaches the first port H on the compression stroke, whereupon the pressure in the chamber B' being thus relieved the non-return valve C' will close and no further charge will enter the working cylinder. If one or more of the ports H are closed by the valve H² the closing of the valve C' will be delayed accordingly and the charge which enters the working cylinder correspondingly increased. The position of the valve H² may be varied automatically by means actuated by a centrifugal governor or otherwise controlled by the speed of the engine. It is advisable to relieve the pressure in the conduit C at the end of the compression stroke and for this purpose a single port such as indicated at K (Fig. 1) may be provided cooperating with a recess K' in the piston, but this relief device need not of course be provided when a device of the kind illustrated in Fig. 3 is used. The conduit E may be provided if desired with an enlargement constituting a storage chamber for the charge compressed in the chamber B' on the outer side of the piston A', as the port E' is prefer-

ably not uncovered until the piston A is practically at the outer end of the chamber. Although the valves C', D', F', are shown as suction valves it will be understood that one or more of them may alternatively be positively actuated if desired; also the ports E' and B' may alternatively be provided with valves, preferably positively actuated.

In the modified construction of Figs. 4 and 5, the duct C is considerably shortened by interposing the valve C' at an intermediate point of its length, the remainder of the duct, which is identified in Fig. 4 by the reference character B° being permanently in free communication with the rear end of the cylinder and forming part of the combustion chamber. The valve arrangements controlling scavenging charge are reversed as compared with the construction of Fig. 1, the charge being admitted to the chamber B' through a suitable duct or ducts, such as the air trunks I formed within the body of the fixed sleeve B², and ports I' connecting the ducts with the chamber B', these ports being covered by the piston trunk until near the end of the return stroke of the piston when the air rushes in to fill the chamber B' and the pipe J which connects the chamber with the cylinder B at any suitable point through a non-return or other suitable valve J'. On the outward or working stroke of the piston this charge is compressed within the chamber B' and pipe J as soon as the piston trunk closes the ports I', and toward the end of the working stroke the compressed charge is admitted to the cylinder B through the opening of the valve J' when the pressure in the cylinder falls below that of the scavenging charge, which then rushes into the cylinder and flushes the combustion products through the exhaust ports B'.

It should be noted that with the engine constructed as herein described and illustrated, the splash system of lubrication commonly used in engines of this type is in no way interfered with, as the crank casing is

not employed as a storage or compression chamber. The piston A may be provided with lateral oil holes A⁶ as shown for the passage of the lubricant to the rubbing surfaces. 50

Having thus described the nature of this invention and the best means we know of carrying the same into practical effect, we claim:

1. In internal combustion engines, a working cylinder, a pump cylinder co-axial therewith, a fixed sleeve within said latter cylinder forming in connection with the cylinder an annular chamber, a trunk piston sliding over the said sleeve and having an annular extension constituting a pump piston working in said chamber, ducts connecting the chamber at the front and rear of the pump piston with the working cylinder and a source of fluid supply, and valves controlling said ducts. 55

2. In internal combustion engines, a working cylinder, a pump cylinder co-axial therewith, a fixed sleeve within said latter cylinder forming in connection with the cylinder an annular chamber, a trunk piston sliding over the said sleeve and having an annular extension constituting a pump piston working in said chamber, ducts connecting the chamber at the front and rear of the pump piston with the working cylinder and a source of fluid supply, valves controlling said ducts, a plurality of ports adapted to communicate with said chamber, a channel in the trunk piston adapted to establish such communication, and means for closing the outer ends of any desired number of said ports. 70

In testimony whereof we have signed our names to this specification in the presence of 85 two subscribing witnesses.
